UNITED STATES PATENT OFFICE.

HUBERT WITTE, OF ST. LOUIS, MISSOURI, ASSIGNOR TO ST. LOUIS CAR COMPANY, OF ST. LOUIS, MISSOURI, A CORPORATION OF MISSOURI.

CAR-SEAT.

SPECIFICATION forming part of Letters Patent No. 787,603, dated April 18, 1905.

Application filed April 29, 1904. Serial No. 205,575.

To all whom it may concern:

Be it known that I, HUBERT WITTE, a citizen of the United States, residing at the city of St. Louis, State of Missouri, have invented 5 a certain new and useful Improvement in Car-Seats, of which the following is a full, clear, and exact description, such as will enable others skilled in the art to which it appertains to make and use the same, reference 10 being had to the accompanying drawings, forming part of this specification, in which—

Figure 1 is an end elevation. Fig. 2 is a front view, partly in section, on about the line 2 2 of Fig. 1 of one end of the seat; and Fig. 15 3 is a fragmentary detail, the supporting-lever being removed and certain of the parts being broken away.

This invention relates to improvements in car-seats, my object being to provide a seat 20 of simple and convenient construction and of easy operation.

To these ends and also to improve generally upon devices of the character indicated the invention consists in the various matters 25 hereinafter described and claimed.

Referring now more particularly to the drawings, 1 indicates an end support or casting. 2 is a saddle pivoted upon said end support at 3, and 4 is the seat proper, which is 30 supported upon the saddle in any convenient or well-known manner. The seat-back is connected to carrying-levers 5, and these carrying-levers are pivotally connected to the upper ends of supporting-levers 6, the lower 35 ends of said supporting-levers being pivoted at 7 upon the end supports below the seat proper and in substantially the transverse center of the seat.

Formed upon the inner side of each end plate 40 1 is a segmental rack 8, and above this rack a segmental slot 9 is formed in each end plate. A shaft 10 extends between the supporting-levers 6 and is rotatably mounted in them.

Gear-blocks connected to this shaft to rotate 45 therewith have each a substantially cylindrical portion 11, which extends through one

of the before-mentioned segmental slots 9, and upon each side of this cylindrical portion is a gear, the inner gear being marked 12 and the outer gear 13. The inner gear meshes 50 with the before-mentioned segmental rack 8, while the outer gear meshes with a segmental rack 14, formed upon the lower end of the back-carrying lever 5.

When in either extreme position, the cylindrical portion 11 of each gear-block engages one end of the segmental slot 9, and the carrying-lever 5 is upon one side of the seat proper in position to give the desired inclination to the back, while the rack 14 is in 60 mesh with the pinion or gear 13. When force is applied to the seat-back in a direction toward the opposite side of the seat, the lever 5 cannot have its upper end rocked forwardly 65 upon the pivotal connection between said lever and its supporting-lever 6, for the lever 5 can rock only upon movement of the gear-block, and movement of said block to permit forward rocking of the upper end of the seat-back is prevented by reason of the fact that 70 the cylindrical portion of the gear-block engages one end wall of the slot 9 and the gear 12 is in mesh with the rack 8. When, therefore, force is applied to the seat-back in a direction tending to move said back toward the 75 opposite side of the seat, the supporting-lever 6 rocks upon its pivot 7, and the gears of course move bodily with said supporting-lever. As the gear-block moves toward the opposite side of the seat the coöperation between 80 the rack 8 and the pinion 12 causes the gear-block to be rotated, and such rotation of the pinion 13, meshing with the rack 14, causes the carrying-lever 5 to be rocked upon its pivotal connection with the supporting-lever 85 6, the inclination of the carrying-lever, and consequently of the seat-back, being reversed as the seat-back is thrown into its new position.

Each saddle-plate 2 lies adjacent one of the 90 end supports 1 and has a cam-slot 15, the before-mentioned cylindrical portion 11 of the

gear-block being of sufficient length to extend through not only the slot 9 of the end support, but also the said cam-slot 15 of the adjacent saddle-plate. Therefore as the carrying-lever 6 swings from one side to the other of the seat the said cylindrical portion 11 of the gear-block coöperates with the wall of its receiving cam-slot 15 to rock the saddle upon its pivot, and thus reverse the inclination of the seat proper in a manner which will be readily apparent.

Extending from the lower portion of each supporting-lever 6, and preferably integral with said respective levers, are foot-rest arms 15 and 17, these arms extending upon opposite sides of the supporting-lever. Foot-rest rails 18 connect similar arms at opposite ends of the seat, so that, as illustrated in Fig. 1, when the seat-back is at one side of the seat 20 the foot-rest upon said side is in operative position, while the opposite foot-rest is thrown up out of the way in order to permit satchels and the like to be inserted under the seat, the positions of the foot-rest rails being reversed 25 in a manner which will be clearly apparent as the seat-back is thrown from one side of the seat to the other thereof.

I am aware that minor changes in the construction, arrangement, and combination of 30 the several parts of my device can be made and substituted for those herein shown and described without in the least departing from the nature and principle of my invention.

Having thus described the invention, what 35 is claimed as new, and desired to be secured by Letters Patent, is—

1. In a car-seat, the combination with a seat proper, a seat-back, rockable levers arranged on each side of the back for pivotally supporting the same, seat-tilting members carried by 40 said back-supporting levers, and a connection between the back below its pivotal point and said seat-tilting members for tilting the back in opposite directions and for causing each of the seat-tilting members to alternately contact with a portion of the seat near its respective longitudinal edges whereby said seat will be tilted: substantially as described.

2. In a car-seat, the combination with a seat 45 proper, and a back movable from one side of the seat to the other thereof, of a movable supporting member upon which said back is pivoted, a gear carried by said supporting member, a rack over which said gear travels as said supporting member is moved from one side of said seat to the other thereof, a rack upon said seat-back, and operative connection between said rack and said gear; substantially as described.

3. In a car-seat, the combination with a seat proper, and a seat-back, of a supporting-lever to which said seat-back is pivoted, a gear carried by said supporting-lever, a rack over which said gear moves, a rack upon said

seat-back, and operative connection between 65 said rack and said gear; substantially as described.

4. In a car-seat, the combination with a seat proper, and a seat-back movable from one side of said seat to the other thereof, of a movable 70 supporting member to which said seat-back is pivoted, a gear carried by said supporting member, a rack over which said gear travels, a second gear connected to said first gear, and a rack upon said seat-back coöperating with 75 said second gear; substantially as described.

5. In a car-seat, the combination with a relatively fixed member provided with a slot, a seat proper, and a seat-back movable from one side of said seat to the other thereof, of a supporting member to which said seat-back is pivoted, a revolving pinion carried by said supporting member, a rack over which said pinion travels from end to end, operative connection between said pinion and said seat-back 85 for rocking the latter upon its pivot, and a member connected to said pinion and received in said slot, whereby the walls of said slot serve to limit the movement of said pinion; substantially as described.

6. In a car-seat, the combination with an end support having a slot, a seat proper, and a seat-back movable from one side of said seat proper to the other thereof, of a movable supporting member to which said seat-back is pivoted, a 95 rotatable member carried by said supporting member and extending through said slot, a gear upon one end of said rotatable member, a rack over which said gear travels, a second gear upon said rotatable member and at the 100 other end of the same, and a rack upon said seat-back and coöperating with said second gear; substantially as described.

7. In a car-seat, the combination with a frame member, a seat proper, a seat-back movable from one side of said seat proper to the other side thereof, levers pivoted below the seat and pivotally supporting said back, a segmental rack, a pinion movable over said rack, and a rack rigid with the seat-back and engaging said pinion; substantially as described.

8. In a car-seat, the combination with a seat proper, a seat-back, rockable levers arranged on each side of the back for pivotally supporting the same, members carried by said back-supporting levers to which rotary motion is imparted when the levers are moved, said members being carried intermediate the ends of the levers, and means below the pivotal point of the seat-back and rigid with said seat-back and in engagement with the rotary members whereby the back will be tilted in opposite directions in its shifted positions; substantially as described.

9. In a car-seat, a supporting-lever rockable 125 from one side of said seat to the other thereof, a pivoted back carried by said lever, a rotatable member carried by said lever, means on

the seat-back in engagement with said rotatable member but independent thereof for tilting the back in opposite directions in the shifted positions of the lever, and means on 5 the seat to contact with the rotatable member whereby the seat will be tilted in either of the tilted positions of the seat-back; substantially as described.

In testimony whereof I hereunto affix my signature, in the presence of two witnesses, this 25th day of April, 1904.
